United States Patent Office

Des. 218,911
Patented Oct. 6, 1970

218,911

PORTABLE PHONOGRAPH OR SIMILAR ARTICLE

George M. Buckler, Fayetteville, N.Y., assignor to General Electric Company, a corporation of New York

Filed Jan. 3, 1969, Ser. No. 15,197

Term of patent 14 years

Int. Cl. D14—01

U.S. Cl. D56—4

FIG.1

FIG.2

FIG.3

FIG.4

FIG.5

FIG.6

FIG. 1 is a front, side and top perspective view of a portable phonograph or similar article, showing my new design;

FIG. 2 is a right side elevational view;

FIG. 3 is a left side elevational view;

FIG. 4 is a top plan view;

FIG. 5 is a front elevational view; and

FIG. 6 is a rear elevational view thereof.

I claim:

The ornamental design for a portable phonograph or similar article, substantially as shown.
